(57) **CLAIM**

The ornamental design for a cylindrical pendant storage apparatus, as shown and described.

DESCRIPTION

FIG. 1 is a perspective view of a cylindrical pendant storage apparatus according to our new design.

FIG. 2 is a front elevation view of the cylindrical pendant storage apparatus of FIG. 1.

FIG. 3 is a side elevation view of the cylindrical pendant storage apparatus of FIG. 1; and,

FIG. 4 is a top view of the cylindrical pendant storage apparatus of FIG. 1; and,

FIG. 5 is a bottom view of the cylindrical pendant storage apparatus of FIG. 1.
